UNITED STATES PATENT OFFICE.

CARL F. GEIGER AND FREDERICK C. GEILER, OF DAYTON, OHIO.

REFRIGERATING MACHINE.

Application filed September 19, 1921. Serial No. 501,658.

To all whom it may concern:

Be it known that we, CARL F. GEIGER and FREDERICK C. GEILER, citizens of the United States, residing at Dayton, in the county of 5 Montgomery and State of Ohio, have invented certain new and useful Improvements in Refrigerating Machines, of which the following is a specification.

The principal object of this invention is to 10 provide for domestic and other uses, a mechanical refrigerating machine which is compact in construction, and efficient and economical in use. It is absolutely automatic in operation, and can be readily installed in any refrigerator of the ice-cooled type. Furthermore, it will maintain a lower temperature than ice, and at approximately half the cost of the latter.

Other important and incidental objects 15 will be brought out in the following specification, and particularly pointed out in the subjoined claims.

In the accompanying drawings, Figure 1 is a perspective view of a refrigerator 20 equipped with our improved mechanical cooling means. Figure 2 is an end elevation of the refrigerating unit. Figure 3 is a sectional view taken on the line A—A of Figure 2, showing the compressing and condensing mechanism. Figure 4 is an end sectional view taken on the line B—B of Figure 3, showing the improved stuffing box. Figure 5 is a sectional view taken on the line C—C of Figure 2 showing the automatic controlling means. Figure 6 is a longitudinal sectional view of the expansion valve. Figure 7 is a top plan view of said valve. Figure 8 is a perspective view of the brine tank, showing the freezing compartment and ice drawer. Figure 9 is a longitudinal sectional view of said tank, showing the expansion coil. Figure 10 is a top plan view of said tank, with the top removed. Figure 11 is a perspective view of the ice drawer. And 45 Figure 12 is a section on the line D—D of Figure 5.

Throughout the specification and drawings, similar reference characters denote corresponding parts.

Referring to the accompanying drawings, the numeral 1 designates a refrigerator of a common type, in the ice compartment 2 of which is placed a brine tank 3 constructed as follows. Referring to Figure 8, the tank 3 55 consists of a rectangular box about the size of a hundred pound cake of ice and prefer-

ably constructed of tinned copper. Within the walled interior portion 4 of this tank is preferably placed a solution of calcium chloride which surrounds a tubular copper coil 5 60 connected at one end to the lower end of an expansion valve 6. At its other end the coil is connected, by a tubular fitting 7, to the rear end of the compressor casing 8. (See Figures 1, 3 and 6.)

The front portion of the brine tank 3 is closed by an ornamental plate 9 preferably made of vitreous enameled sheet-iron. This plate is provided with a central opening closed by a hinged door 10, that affords access to the freezing chamber which the coil 5 and the calcium chloride solution surround. (See Figures 8 and 9.) Movable into the bottom portion of the brine tank 3 is an elongated drawer 11, semi-oval shape 75 in cross section, that is divided into a number of compartments 12 to receive water from which ice blocks are formed for table use. The drawer 11 may be readily moved outwardly and inwardly by a finger grip 13 80 on its front end. (See Figures 8 and 11.)

Referring to Figures 3 and 4, the compressor casing 3 has a crank chamber 14 formed between a partition wall 15 and the outer wall of said casing. Mounted in a circular hole in the middle portion of the partition 85 15, is an elongated bearing 16 for a crank shaft 17 on which is fast a crank 18 having a right-angled crank pin 19 to which is secured one end of a connecting rod 20. The inner 90 end of the latter is connected by a wrist pin 21 to a piston 22 movable in a cylinder 23.

The cylinder 23 projects through a hole in a partition wall 24 in the middle portion of the casing 8, to enter a compression chamber 95 25. The rear end of the cylinder 23 is closed by a head 26 in which there is a hole 27 adapted to be opened and closed by a flap valve 28 secured at its lower end to the head 26. (See Figure 3.)

The compression chamber 25 is closed by a removable head 29 secured to the casing 9 by cap screws 30. Mounted on, and projecting through, the head 29 are the inlet and outlet ends 31 and 32 respectively of a coil 105 of copper tubing 33. (See Figure 3.) This coil surrounds that portion of the cylinder 23 that is within the compression chamber 25.

Gas, preferably sulphur dioxide, is drawn 110 into a receiving chamber 34 through the fitting 7 that receives one end of the coil 5.

(See Figures 3 and 4.) This chamber 34 communicates with the crank chamber 14 through arcuate holes 36. Ports 37, 37 are provided in the cylinder 23 to admit the sulphur dioxide gas into the space in it ahead of the piston 22 when a vacuum is created by the forward stroke of the latter. On the return stroke of the piston, this gas is compressed and forced outwardly into the compression chamber 25 through the port 27 past the flap valve 28.

Water, entering the inlet portion 31 of the coil 33, flows through the latter to extract the heat units from the compressed gas, causing the latter to liquify and lie on the bottom of the compression chamber 25 as shown in Figure 3.

The pressure of the gas in the compression chamber 25 above the liquid formed by the condensed gas, forces said liquid into a strainer tube 38 that projects into a fitting 34 secured in the casing 8. A tube 40 received by this fitting, conducts the liquid to a fitting 41 that enters the lower half portion 42 of the expansion valve 6 for communication with a lateral passage 43 that leads to a chamber 44 in said valve. (See Figures 2, 3 and 6.) Projecting downwardly into the chamber 44 is a needle valve 45 adapted to open and close a tapering hole 46 in a seat 47 secured in the lower end of the said chamber. The tube 5 that leads to the brine tank 3, enters a fitting 48 which is screwed on the lower reduced threaded end 49 of the lower section 42 of the expansion valve casing. A bore 50 in this reduced end 49 of the valve casing communicates with the needle opening 46 in the seat 47 to conduct the liquid in its finely divided form to the tube 5, for transference by it to the coil in the brine tank 3.

Again referring to Figure 6, a diaphragm 51 is interposed between the lower section 42 of the valve casing 6 and the upper section 52 of the latter, said sections being compressed against the circumferential edge portion of the diaphragm by screws 53 which pass through holes in the marginal flange portions of said valve casing sections. (See Figures 6 and 7.)

Screwed into the peripheral portion of the top section 52 of the expansion valve, is a fitting 54 which receives a tube 55 that leads to a T 56 on the brine tank 3, for connection through it with the tube 5. (See Figures 2 and 8.) The fitting 54 communicates with the space above the diaphragm 51 through a lateral passage 57 in the wall of the upper section 52 of the valve casing. Screwed on the upper reduced threaded portion 58 of the top section 52 of the expansion valve casing, is a cap 59 which seats on a rubber gasket 60 that rests on a shoulder formed around said reduced portion. Beneath the cap 59 is an adjusting screw 61

having a downwardly projecting spring pilot 62. Said screw is screwed into a threaded bore 63 in the upper section 52 of the valve casing. Surrounding the pilot 62 in said bore is the upper end of a compression spring 64 whose lower end bears against the diaphragm 51.

Surrounding the upper end of the needle valve 45 is a metallic bellows 65 of a well known type, which forms a continuation of the chamber 44. The head 66 of the bellows 65 has a hollow stem portion 67 which projects upwardly through a central hole in the diaphragm 51, to act as a pilot for the lower end of the spring 64, as well as a nut to receive the upper threaded end of the needle valve 45. A washer 68 is soldered on the diaphragm 51 around the stem 67 of the bellows, to seal the chamber on one side of the diaphragm from that on the other side. The chamber above the diaphragm is sealed against the escape of gas, or the admission of air, by the cap 59 and gasket 60,

The operation of the expansion valve 6 will now be described. The refrigerating agent, which in this instance is sulphur dioxide, enters the chamber 44 through the passage 43 from the tube 5, at a predetermined pressure, exerting said pressure against the lower surface of the bellows head 66. This upward pressure is restrained by the spring 64 until a partial vacuum is created above the diaphragm 51 by the suction exerted by the compressor through the tube 55. When a sufficient vacuum is created above the diaphragm 51, the needle valve will be raised above its seat 47 to permit the liquid to be drawn through the needle hole 46 for entrance, in a finely divided state, into the end of the tube 5 received by the fitting 48, passing through said tube to the coiled portion of the latter in the brine tank 3, where it is converted by the absorption of heat from the brine, into a vapor. This withdrawal of heat from the brine, reduces the temperature of the tank, which in turn lowers the temperature of the surrounding atmosphere in the refrigerator containing the tank.

Since the tube 55 is connected by the T 56 to the return portion of the expansion tube 5, any back pressure which would be set up by a flow of gas through the needle opening in the seat 47, in excess of that withdrawn from the expansion tube 5 by the action of the compressor, will decrease the vacuum above the diaphragm 51. This will permit the spring 64 to exert a sufficient counter-pressure against the needle valve 45 to close the opening in the valve seat 47, thus checking any further flow of gas until such time as the compressor will have created a vacuum sufficient to open the needle valve again. (See Figure 6.)

The machine is automatically controlled

by the following means. Referring to Figures 5, 8 and 9, the numeral 69 designates a thermostatic tube which projects upwardly through the top of the brine tank 3 into the calcium chloride solution or brine. On the top of said tube is mounted a gage 70. Connected to, and communicating with, the thermostatic tube 69, is a tube 71 which is connected by a fitting 72 to the head 73 of a horizontally disposed metallic bellows 74. The front portion of the latter is contained within a steel cap 75 secured to an automatic control housing 76. The metallic bellows 74 projects into this housing through a hole 77 in the latter. (See Figure 5.)

The opposite head 78 of the bellows 74 is doweled into one end of a bell crank lever 79 mounted on a pivot pin 80 secured within the housing 76. The other end of said bell crank lever is connected by a link 81 to an arm 82 pivotally mounted on a pin 83 secured in a switch frame 84 mounted in a switch housing extension 85 of the compressor casing 8. (See Figure 5.)

25 Mounted on the base of the switch frame 84 is a transverse insulated block 86 on which is secured a contact 87. Adapted to engage the latter is a brush 88 carried by the insulated end of a brush arm 89 pivotally mounted at its rear end on an upwardly projecting portion 90 of the switch frame. Connected to the free end of the arm 82 is a laminated spring 91, the lower end of which is secured to the free end of a trip trigger 92 pivotally secured within the slotted portion 93 of the brush arm 89. (See Figure 5.)

Supported by a bearing block 94 mounted on the base of the switch frame 84, is a bell crank lever 95, the vertical end of which terminates in a hook shaped head 96 below which is a notch 97. Adapted to be engaged by the notched portion 97 of the bell crank lever 95, is a catch plate 98 secured to the free end of the brush arm 89. When the outer edge of this plate 98 is engaged by the notched portion 97 of the lever 95, the brush 88 will be held in firm engagement with the contact 87, to close an electric circuit 40 through wires 99 and 100 which lead to an electric motor 101 that drives the compressor or through an endless chain 102 which passes around a sprocket wheel 103 fast on the crank shaft 17. (See Figures 4 and 5.)

55 The electric circuit is broken when the notched portion 97 of the bell crank lever 95 is withdrawn from engagement with the plate 98. The outward movement of the upper end of this bell crank lever 95 to disengage its notched portion 97 from said plate, is accomplished as follows: The opposite end of the bell crank lever 95 is in the path of downward movement of the free end of the trigger 92 which, when forced 60 over center by the arm 82, will be snapped

into engagement with the outer end of the horizontal portion of the bell crank lever 95 to withdraw the notched portion 97 on its other end from engagement with the catch plate 98. When the trigger 92 passes below center, it will impart a sudden upward movement to the free end of the brush arm 89, which will continue its upward movement until restrained by the hook-shaped head 96 of the bell crank lever. The 75 upward movement permitted the free end of the brush arm, is sufficient to cause the latter to disengage the brush 88 from the contact 87 to break the electric circuit to the motor. 70

When the gas in the thermostatic tube 69 is contracted, due to the lowering of the brine temperature, it will reduce the pressure of the gas in the metallic bellows 74. This reduction of pressure will permit a suspension spring 104 to exert a pull upon 80 the upper end of the bell crank lever 79 to raise, through the link 81, the front end of the arm 82. When the front end of the latter is raised, its rear end will be depressed to force the trigger 92 downwardly 85 to break the contact in the manner just described. It is thus seen that when the temperature of the brine in the tank 3 is lowered, the motor 101 will be stopped until the temperature of the brine rises sufficiently 90 to expand the gas in the thermostatic tube 69 to set up a pressure in the metallic bellows 74 that will overcome the tension of the spring 104. One end of the latter is connected by a pin 105 to ears 106 on the upper end of the bell crank lever 79, while the other end of said spring is connected to a screw eye 107 adjustably secured to a washer 108 that covers a hole in the automatic control housing 76. Threaded on the outer 100 end of the screw eye 107 is a nut 109 by means of which the screw eye may be longitudinally adjusted to vary the tension of the spring to make the automatic operation 105 of the switch responsive to any desired 110 temperature of the brine tank. (See Figure 5.)

The admission of water to the coil 33 in the compression chamber 25, is automatically controlled by the following means. The 115 inlet tube 31 is connected by a fitting 110 to a water valve casing 111 which is secured in the automatic control housing 76. (See Figure 5.) A water supply pipe 112 is connected by a fitting 113 to the end portion 120 of the casing 111. Projecting into said casing through a packing 114 secured in its other end, is a needle valve 115. The latter has an outer threaded end which projects through a hole in the lower end of a lever 125 116 which is fulcrumed on the pin 80, straddling the bell crank lever 79 which is also fulcrumed on said pin. (See Figures 5 and 12.) Nuts 117 and 118 are placed on the threaded end of the needle valve 115, 130

one on each side of the lever 116, to adjust the proper movement of the needle valve by the lever.

5 Into the upper end of the lever 116 is dowelled the head 119 of a metallic bellows 120 which projects outwardly through a hole 121 in the automatic control housing 76 into a steel cup 22 secured to said housing. The outer head 123 of the metallic bellows 120 10 has a tubular portion 124 which projects through the cup 122 to receive a fitting 125 that in turn receives one end of a tube 126 whose other end is connected by a fitting 127 to the compressor casing 8 for communication with the compression chamber 25 therein. (See Figures 3 and 5.)

Connected by a pin 128 to ears 129 on the lever 116, is one end of a suspension spring 130 whose other end is connected to a screw 20 eye 131 adjustably secured to a washer 132 that covers a hole in the automatic control housing 76. (See Figure 5.) Threaded on the outer end of the screw eye 131 is a nut 133 by means of which the screw eye may 25 be longitudinally adjusted to vary the tension of the spring 130.

Mounted upon the casing 8, and communicating with the compression chamber 25 therein, is a gage 134 which indicates the 30 pressure of the gas within said chamber. Now when the pressure of the gas in said chamber rises above a predetermined reading on the gage, say thirty four pounds, the pressure of the gas in the metallic bellows 35 120 will overcome the tension of the spring 130, said gas being conducted to said bellows through the tube 126. Therefore, the bellows 120 will exert a sufficient pressure upon the upper end of the lever 116 to cause the 40 lower end of the latter to pull the needle valve 115 from its seat, thus permitting water to flow past it into the inlet tube 31, which conducts said water to the condenser coil 33 within the compression chamber 25. 45 When the water passes through the coil 33, it will lower the temperature of the surrounding gas sufficiently to cause it to liquefy, thereby reducing the pressure of the remaining gas to a normal working pressure.

50 Now when the gas in the compression chamber 25 reaches, or goes below, its normal working pressure, its pressure in the metallic bellows 120 will be reduced sufficiently to cause the spring 130 to exert a pull 55 upon the lower end of the lever 116 to cause it, in turn, to force the needle valve 115 tightly against its seat, thus checking a further flow of water to the coil 33, as when the motor is idle.

60 Should the water at any time be turned off ahead of the valve 111, the pressure of the gas in the metallic bellows 120 would become so great as to force the head of a screw 135 on the upper end of the lever 116, into engagement with the upper end of the bell

crank lever 79, to move the latter a sufficient distance to disengage the switch, thereby stopping the motor 101. (See Figure 5.) Assurance is thus given that no damage will result to the mechanism through the shutting off of the water in the main line. The screw 135 can be set to engage the upper end of the bell crank lever 79 to cause the latter to disengage the switch when the pressure of the gas in the metallic bellows 120 75 rises to a predetermined point—in the present instance being sixty pounds.

Referring to Figure 4, the crank shaft 17 passes through a stuffing box 136 secured in the compressor casing 8. This stuffing box 80 has a corrugated periphery to present a large surface to the gas which flows around it in the chamber 34, on its way to the crank case 14. It is thus seen that the cool gas returning from the expansion coil in the brine tank 3, by flowing over the stuffing box 136, will prevent it from heating, thereby minimizing friction therein.

Surrounding the shaft 17 is a coil spring 137 which exerts sufficient pressure against 90 the metallic packing 138 in the stuffing box 136 to prevent any leakage of gas past it. The tension of this spring 137 is adjusted by a nut 139 which receives the head of the spring, and screws into the stuffing box. 95 (See Figure 4.)

Referring to Figure 4, there is provided in one end of the crank chamber portion of the casing 8 a partition 140 between which and the removable cover 141 of said casing is an oil chamber 142. This chamber contains oil in which the sprocket wheel 103 and the chain 102 which drives it, runs. This construction insures proper lubrication of the 100 said driving elements.

Cast on top of the casing 8 is a pair of ears 143, 143 in which is secured a transverse pin 144 on which is pivotally mounted a base plate 145 on which is secured by bolts 146, 146, the base portion of the motor 101. 110 (See Figures 3 and 4.) A stud 148 projecting upwardly from the casing, loosely passes through a hole in the base plate 145. Two nuts, 149 and 150, are placed on the outer end of this stud, one on each side of the 115 base plate 145, to adjust the angular position of the outer end of the base plate, and through it, the angular position of the motor to take up any slack in the chain 102.

While the refrigerating unit may be 120 placed anywhere, it is shown in Figure 1 as mounted upon a base 151 suspended by rods 152 secured to floor joists 154 below a floor 155 upon which the refrigerator 1 is mounted.

We do not wish to be limited to the details of construction and arrangement herein shown and described, and any changes or modifications may be made therein within the scope of the subjoined claims. 130

1. In a refrigerating apparatus, the combination with a compressor, of an expansion coil, a refrigerant line leading from said compressor to the expansion coil, means for returning cool gas from the latter to the compressor, a shaft for the compressor, and packing means surrounding said shaft in the path of the cool gas returned to the compressor from the expansion coil.
2. In a refrigerating apparatus, the combination with a compressor, of an expansion coil, a refrigerant line leading from said compressor to the expansion coil, means for returning cool gas from the latter to the compressor, a shaft for the compressor, and externally corrugated packing means surrounding said shaft in the path of the cool gas returned to the compressor from the expansion coil.
3. In a refrigerating apparatus of the type described, the combination with a casing, of a compressor therein, an expansion tank, a refrigerant line leading from said casing to the expansion tank, a return line leading from the latter to said casing, a crank shaft in the latter for the compressor, and a stuffing box for said crank shaft, located in said casing in the path of the gas returned to it by said return line, for the purpose specified.
4. In a refrigerating apparatus of the type described, the combination with a compressor casing, of a crank chamber in the latter, a crank shaft in said chamber, a gas receiving chamber communicating with the latter, and through which said crank shaft projects, a compressor driven by said shaft, in said casing, an expansion tank, means for returning cool gas from the latter to the receiving chamber in the compressor casing, and a stuffing box for the crank shaft, in the gas receiving chamber, in the path of the incoming gas from the expansion tank.
5. In a refrigerating apparatus of the type described, the combination with a compressor casing, of a compressor in the latter, a crank shaft for said compressor, mounted in said compressor casing, an expansion coil, means for returning cool gas from the latter to the compressor casing, and a stuffing box having a corrugated periphery, through which said shaft projects, located in the compressor casing opposite the cool gas returning means.

In testimony whereof we have hereunto set our hands this 14 day of September 1921.

CARL F. GEIGER.

FREDERICK C. GEILER.

Witness:

HOWARD S. SMITH.
